DESIGN FOR A WATCHCASE

Maurice Merz, New York, N. Y., assignor to The Longines-Wittnauer Co. Inc., New York, N. Y.

Application January 14, 1938, Serial No. 74,299

Term of patent 7 years

To all whom it may concern:

Be it known that I, Maurice Merz, a citizen of the United States, residing at New York city, New York, have invented a new, original, and ornamental Design for a Watchcase, of which the following is a specification, reference being had to the accompanying drawing, forming a part thereof.

Fig. 1 is a top plan view of a watchcase showing my new design.

Fig. 2 is an edge view thereof.

I claim:

The ornamental design for a watchcase, as shown.

MAURICE MERZ.
